UNITED STATES PATENT OFFICE.

PERLEY H. OVERPECK, OF ROCKVILLE, INDIANA.

MAIL-CATCHER.

1,114,025.

Specification of Letters Patent. Patented Oct. 20, 1914.

Application filed March 17, 1914. Serial No. 825,340.

To all whom it may concern:

Be it known that I, PERLEY H. OVERPECK, a citizen of the United States, residing at Rockville, in the county of Parke and State 5 of Indiana, have invented certain new and useful Improvements in Mail-Catchers, of which the following is a specification.

This invention relates to a mail catcher, and the principal object of the invention is 10 to provide a mail catcher in which there is provided pivotally mounted jaws held in an open position by means of springs which also open to move the jaws to a closed position when the jaws are struck by the mail 15 bag striking a sliding plate carried by the base plate of the mail catcher.

Another object of the invention is to provide improved means for slidably mounting the spring-carrying rods and to so mount 20 the jaws and spring-carrying rods that the springs will hold the jaws in an open position without the employment of any auxiliary holding means.

Another object of the invention is to 25 provide a mail catcher which will be very simple in construction, and which can be very cheaply made.

This invention is illustrated in the accompanying drawings wherein—

30 Figure 1 is a top plan view of the improved mail catcher in a set position; Fig. 2 is a view similar to Fig. 1 with the jaws moved to hold a mail sack; Fig. 3 is a transverse sectional view taken along the line 3—3 of Fig. 35 2; Fig. 4 is a fragmentary sectional view taken along the line 4—4 of Fig. 1.

The jaws 10 are pivotally connected with the base plate 11 by means of pivot bolts 12 which extend through the bearings 13 40 formed adjacent the inner ends of the jaws. These jaws are pivotally mounted upon opposite sides of the abutment plate or trigger 14 which is slidably connected with the base plate by means of bolts or pins 15 45 which extend through slots 16 formed in the plate 14. Angle irons 17 are secured to the base plate adjacent the forward corners of the same and form abutments to limit the pivotal movement of the jaws when 50 closing, as shown in Fig. 2. It will thus be seen that the jaws can not close beyond a desired amount, and that, therefore, there will be no danger of articles placed in the mail bag being crushed or broken.

55 Fingers 18 are pivotally connected with

the inner ends of the jaws 10 and have their free end portions provided with longitudinally-extending slots 19 so that the fingers 18 may be slidably mounted upon the pin 20. This pin 20 is provided with an enlarged head 21 and with abutment shoulders 22 and 23. The abutment shoulder 22 is positioned between the fingers 18 and the abutment shoulder 23 engages the base plate 11 so that when the nut 24 is tightened, the pin 21 will be securely held in place. These fingers 18 carry spindle springs 25 which are placed upon the fingers between the pin 20 and collars 26 and serve to hold the jaws in either the position shown in Fig. 1 or 70 that shown in Fig. 2.

When setting the mail catcher, the jaws 10 are moved outwardly to the position shown in Fig. 1 and this operation will swing the inner ends of the jaws inwardly 75 to compress the springs 25. The inner ends of the jaws swing inwardly to such an extent that the springs will tend to move the inner ends toward the trigger plate 14 and thus hold the jaws in the open position and hold the trigger plate in the set position as shown. When the mail bag strikes the trigger plate, the plate will be driven inwardly and this will cause the plate to move the inner ends of the jaws outwardly beyond a 80 dead center so that the springs can expand and swing the jaws to the position shown in Fig. 2 and cause them to be held tightly about the mail sack which is indicated by dotted lines in Fig. 2. Angle irons 17 prevent the jaws from being moved in this direction beyond a desired amount thus preventing the mail bag from being clamped too tightly and also preventing the fingers 18 from moving out of engagement with the 95 pin 20.

I have therefore provided a mail catcher which is very simple in construction and which will be cheap to manufacture and easy to set up. It should be noted that if 100 desired a cover plate similar to the base plate may be provided and secured by any suitable means. If desired, the pivot bolts 12 can be used for securing the cover plate. It should also be noted that the outer face 105 of the trigger plate is curved and that the outer edge of the base plate is also curved so that the base plate and trigger plate will conform to the contour of a mail bag. This construction will assist in preventing the 110

contents of the mail bag from being crushed or broken.

What is claimed is:

1. A mail bag comprising a base plate, jaws pivotally connected with said base plate, fingers pivotally connected with the inner ends of said jaws, a guiding pin slidably engaged by said fingers to guide the sliding movement of said fingers, spindle 10 springs mounted upon said fingers and engaging said pin, abutments carried by said fingers and engaging the opposite ends of said springs whereby said springs will serve to yieldably hold said jaws in an open and 15 in a closed position, a trigger plate slidably connected with said base plate between said jaws for engaging the inner end portions of said jaws, and abutments carried by said base plate for limiting the pivotal movement 20 of said jaws in one direction and prevent said jaws from closing beyond a desired amount.

2. A mail catcher comprising a base plate, jaws provided with bearings adjacent their inner ends, pivot pins carried by said base plate and passing through said bearings to pivotally mount said jaws, a guide pin carried by said base plate, fingers pivotally connected with the inner ends of said jaws and provided with slots through which said guide pin passes, abutments carried by said fingers adjacent said jaws, spiral springs mounted upon said fingers between said pin and said abutments, means for limiting the pivotal movement of said jaws in one direction, and a trigger carried by said plate between said jaws for engaging the inner end portions of said jaws when moved inwardly and swing said jaws past a dead center to 40 permit said springs to move said jaws to a closed position.

3. A mail catcher comprising a base, jaws pivotally connected with said base, a guide carried by said base, fingers pivotally connected with said jaws and slidably connected with said guides, resilient means mounted upon said fingers and engaging said guide to form resilient means for releasably holding said jaws in an open position and for moving said jaws to a closed position, and a trigger carried by said base between said jaws for engaging the inner ends of the same when moved inwardly to swing said

jaws toward a closed position and permit said springs to close said jaws.

55

4. A mail catcher comprising a support, jaws pivotally connected with said support, a trigger plate slidably connected with said support between said jaws and engaged by said jaws when the same are moved to a set 60 position, a guide carried by said base, fingers pivotally connected with the inner end portions of said jaws and slidably connected with said guide, and resilient means mounted upon said fingers between said guide and the pivot ends of said fingers.

5. A mail catcher comprising a base, gripping means movably connected with said base, a trigger carried by said base and operated by a sack to move said gripping means from a set position, and common means for releasably holding said gripping means in a set position and moving said gripping means to a closed position after being partially moved from a set position 75 by said trigger.

6. A mail catcher comprising a support, gripping means pivotally connected with said support, a trigger carried by said support for moving said gripping means from 80 a set position, a guide carried by said support and provided with abutment collars, fingers extending from said gripping means and provided with longitudinally-extending slots through which said guide passes, said 85 fingers being positioned upon said guide between said shoulders, and resilient means mounted upon said fingers between said gripping means and said guide.

7. A mail catcher comprising a base, gripping means carried by said base, resilient means for yieldably holding said gripping means in a set position and for moving said gripping means to an operative position, and means carried by said base for moving 95 said gripping means toward an operative position to permit said resilient means to move said gripping means to an operative position.

In testimony whereof I affix my signature 100 in presence of two witnesses.

PERLEY H. OVERPECK.
